Greenleaf Stackpole

United States Patent Office.

GREENLEAF STACKPOLE, OF ELIZABETH, NEW JERSEY.

Design No. 4,729, dated March 21, 1871.

DESIGN FOR A WHISK BROOM.

The Schedule referred to in these Letters Patent and making part of the same.

I, GREENLEAF STACKPOLE, of Elizabeth, in Union county and State of New Jersey, have invented and produced a new and original Design for Whisk-Broom Handles, of which the following is a specification.

The nature of my design is fully represented by the accompanying drawing, to which reference is made, and consists in covering the handle from the ends of the hurl to the end of the handle with a ferrule of wire or solid metal, with the end of the handle wound with colored cord, forming what I call a turban or Turk's head, it having somewhat that appearance.

In fig. 1—

The letter A is the hurl.
B is the ferrule.
C is the cord covering.
Having described my invention,
What I claim as my invention, and desire to secure
by Letters Patent, is—
The whisk-broom handle, as above shown and de-
scribed.

GREENLEAF STACKPOLE.
